M. R. FOSTER

TELEPHONE COVER

Filed July 29, 1921

M. R. Foster,
INVENTOR.

ATTORNEY.

UNITED STATES PATENT OFFICE.

MARY ROBERTS FOSTER, OF WASHINGTON, DISTRICT OF COLUMBIA.

TELEPHONE COVER.

Application filed July 29, 1921. Serial No. 488,319.

To all whom it may concern:

Be it known that I, MARY ROBERTS FOSTER, a citizen of the United States, residing at Washington, in the District of Columbia, have invented certain new and useful Improvements in Telephone Covers, of which the following is a specification.

This invention appertains to a certain novel form of telephone cover, and has for its principal object to provide a type of the same in the nature of a dress adapted to enclose and otherwise cover up practically all of the exposed parts of a telephone, preferably a telephone of the desk or portable type, and in a manner to render the same ornamentally attractive and pleasing to the eye, but without detracting from the general utility of the telephone, or otherwise rendering the same inconvenient or annoying in use.

Another object of the invention is to provide for a cover of the class mentioned, and one which may be readily and quickly applied to a telephone after the manner of a "slip-on" dress or cover, and secured in position thereon for use until soiled or otherwise unfit for further use, when the same can be removed with equal facility for cleaning purposes or for the substitution of another therefor.

A further object of the invention is to provide for a cover or dress as characterized, and one which may be easily made up in any number of designs or materials, either plain or with fanciful trimmings such as will meet with the varying ideas and needs of the trade.

Another object of the invention is to provide for a telephone cover or dress of the character set forth, and one which is capable of being manufactured at an extremely low cost, and made up either singly, or in small or large quantities, without seriously affecting any marked variation in such cost, which cost, however, will mainly depend upon and be determined by the quality of the materials used in the construction thereof.

With the foregoing and other objects in view, the invention resides in the certain

novel and useful construction and arrangement as will be hereinafter more fully described, set forth in the appended claims, and illustrated in the accompanying drawing, in which:

55

Figure 1 is a front elevation of a conventional form of desk or portable type of telephone, showing a preferred embodiment of the invention as applied thereto.

Figure 2 is a vertical section through the cover or dress, the same being taken on the line 2—2 of Figure 1.

Figure 3 is a side elevation.

Figure 4 is a side elevation of the receiver portion of the cover or dress of the telephone, and

Figure 5 is an enlarged fragmentary section through the telephone standard covering portion of the cover or dress and showing the manner of fastening the adjacent edges thereof together.

Referring to the drawing, the letter *a* indicates the base of a desk or portable form of telephone, *b* the standard thereof, *c* the pivot connecting the upper end of the standard *b* for the attaching thereto of the transmitter *d*, *e* the mouth-piece of the transmitter *d*, and *f* the receiver hook and switching arm thereof, all of conventional form, construction and arrangement.

80

The present embodiment of the cover or dress for enclosing the telephone comprises a transmitter covering or upper section substantially of elbow contour, a standard covering or intermediate section of cylindrical contour, a base covering or lower section or flaring contour, and a receiver covering section substantially bell shaped. The upper portion 10 of a fully flexible material or fabric, which is made with a sufficient fullness to be readily fitted over the transmitter *d* to fully enclose the same and the pivot connection *c* thereof, an opening 11 being provided in the upper end of the portion 10 whereby to have inserted therethrough the mouth-piece *e* for its connection with the transmitter *d*, the mouth-piece *e* being removed from the latter previous to the placing of the portion 10 in position. The lower end of the portion 10

85

90

95

100

is formed to provide an opening 12 to snugly fit around the extreme upper end of the standard *b* and the edge of this opening 12 may be rolled or otherwise fancifully plaited 5 or gathered as at 13, as is also the edge of the upper opening 11, as at 14, the latter being provided with a circlet of braiding, edging or the like 15, to add to the attractiveness of the construction. Secured to the 10 inner wall of the lower opening 12 of the upper portion 10 is an intermediate portion 16, which is arranged to encircle and enclose within the same the standard *b* of the telephone, and this portion 16 may be of a similar material or fabric as that of the 15 upper portion 10, but is preferably made of a heavier material or fabric, such as plush or the like. Secured to the lower end of the intermediate portion 16 is a lower portion 20 or skirt 17 which is arranged to entirely cover the upper conical surface of the base *a* of the telephone, and this portion of the cover or dress is gathered at the upper edge thereof to admit of its proper connection with the lower end of the intermediate portion 16, and, at the same time, gives sufficient fullness to the body of the skirt and the lower portion thereof to effect the covering of the base *a* in an attractive 25 manner. The upper open connected end of the skirt portion 17 may have the edge of the opening thereof rolled, plaited or gathered as at 18, after the manner of the rolls or beads 13 and 14 of the upper portion 10 of the cover or dress.

The opposite side edges of the lower portion of the upper part 10 of the cover or dress are normally left unconnected one from the other and correspondingly with 40 the aligning side edges of the intermediate portion 16, and the lower portion of the skirt 17, whereby to admit of the drawing of the cover or dress over the upper end of the telephone, when these side edges will be 45 fastened together by means of a series of fastenings 19, such as the so-called "invisible" snap fastenings and the like, the intermediate portion 16 of the cover or dress fitting the standard *b* in a snug manner, when fastened in position thereon, so as to afford an efficient gripping surface, when the telephone is being used, the receiver hook or switching arm *f* of the telephone being allowed to project from between the 50 adjacent side edges at the upper end of the intermediate portion 16, substantially as is shown in Figure 3.

Supplemental to the cover or dress for the telephone proper, a cover portion 20 is 60 provided for enclosing the receiver thereof, and the same is of a form to snugly adapt itself to the configuration of the same, substantially as is shown in Figures 1 and 4, the lower end of the portion 20 being open 65 so as to not in any way interfere with the use

of the receiver, and the edge of this opening may be gathered or plaited as at 21 in a manner to retain this end of the cover in engaged position. The upper end of this cover 20 is gathered as at 22 to restrict the opening 70 therein for its snug engagement over the end of the receiver which is attached to the conductors leading from the telephone to the same. The upper portions of the seam 23 connecting the side edges of the material or fabric, from which the supplemental cover or dress is made, are left normally unconnected one from the other, whereby to admit of the latter being drawn into enclosing position over the receiver, and these portions are then secured together by means of an invisible fastening or fastenings 24, when the cover or dress will be retained in position until it is desired to remove the same for cleaning or change. To add to the attractiveness of the supplemental cover or dress, a tassel or other similar ornament 25 is attached to and suspended from the upper end thereof by means of a cord or the like 26.

From the foregoing, it will be readily apparent that the invention provides for an extremely novel form of cover or dress for telephones and one that is designed to meet a popular demand for the making of house or private telephones ornamental as well as useful, such as has heretofore been accomplished only by the enclosing of a telephone within fanciful cabinets or coverings not attached directly to or carried by the same, and which have to be opened or otherwise entirely removed to allow for the use thereof.

It is well understood that, while a preferred embodiment of the invention has been described and illustrated herein in specific terms and details of construction and arrangement, various changes in and modifications of the same may be resorted to without departing from the spirit of the invention, or the scope of the claim appended 110 hereto.

Having thus fully described the invention, what is claimed, is:—

A cover comprising an angle shaped hollow upper section having the free terminus of its horizontal leg inturned to form a reduced lateral opening, the lower terminus of the vertical leg of said section providing a vertically disposed opening, a reinforcing element secured to the inturned portion of the horizontal leg of said section and surrounding said lateral opening, a vertically disposed hollow cylindrical intermediate section having its upper end extending into said vertical opening and connected to said upper section, a flaring base section having its top formed with a vertical opening into which extends the lower end of the intermediate section, the said intermediate section being secured at its lower end to the base 130

section, said upper section having its vertical leg split for a portion of its length, said intermediate and said base sections being split throughout, means for detachably connecting the sides of the split portion of the upper section in overlapping position, means for detachably connecting the inter-

mediate section overlapped at the split portion thereof, and means for detachably connecting the base overlapped at the split portion thereof. 10

In testimony whereof I affix my signature hereto.

MARY ROBERTS FOSTER.
